Term of patent 14 years

Int. Cl. D4—01

U.S. Cl. D86—11

FIG. 1 is a top view of the unitary shoe cleaning and polishing device pictured in assembled relationship in FIG. 2.

FIG. 2 is a side view of the device showing our original, new design in fully assembled relationship.

FIG. 3 is a rear view of the working overcap-actuator head which is firmly affixed to both ends of the device shown in FIG. 2.

FIGS. 4, 5 and 6 show respectively the side, top and rear views of a working overcap-actuator head to be alternatively used with the device pictured in FIG. 2 in substitution for the head pictured in FIGS. 1, 2, and 3.

FIGS. 7, 8 and 9 show respectively the front, rear and top-side (in isometric projection) views of yet another working overcap-actuator head to be alternatively used with the device pictured in FIG. 2 in substitution for the head pictured in FIGS. 1, 2 and 3.

FIGS. 10, 11 and 12 show respectively the front, top and top-rear (in isometric projection) views of yet another working overcap-actuator head to be alternatively used with the device pictured in FIG. 2 in substitution for the head pictured in FIGS. 1, 2, and 3.

We claim:

The ornamental design for a unitary shoe cleaning-polishing device, substantially as shown and described.
